UNITED STATES PATENT OFFICE.

JOHN C. GOULD, OF CHICAGO, ILLINOIS.

NAIL-PLATE FEEDER.

SPECIFICATION forming part of Letters Patent No. 315,019, dated April 7, 1885.

Application filed May 17, 1884. (No model.)

To all whom it may concern:

Be it known that I, JOHN C. GOULD, a citizen of the United States, residing at Chicago, in the county of Cook and State of Illinois, have 5 invented a new and useful Improvement in Nail-Plate Feeders, of which the following is a specification.

This invention relates to the construction of the parts of nail-plate feeders, whereby the 10 barrel is supported and operated, and particularly to the kind of feeder shown in the Letters Patent to me of January 22, 1884, No. 292,299. As heretofore made there has been great difficulty in adjusting these parts when 15 it was desired to change the character of the work to be done, or when the parts were out of adjustment and it was desired to properly position them. To ease this adjustment has been the principal object of the present invention, 20 which consists in the combination, in a nail-plate feeder, of the barrel and a standard for the same adjustable upon a circular line whereof the cutting-point of the machine is the center, and whereby the standard may be 25 adjusted without destroying the proper position of the nose of the barrel at the knives.

The invention further consists in the novel construction and combinations of the several parts, as hereinafter fully set forth.

30 In the accompanying drawings, which form a part of this specification, and in which similar letters of reference indicate like parts, Figure 1 is a side view of the parts of the machine to which my invention relates. Fig. 2 is a central longitudinal vertical section of the 35 same. Fig. 3 is a rear view. Figs. 4 and 5 are horizontal sections on the lines 44 and 55, respectively, of Fig. 3. Fig. 6 is a detail section of one of the supporting-brackets. Fig. 40 7 is a section on line 77 of Fig. 1.

In the drawings, A represents the block whereon the stationary knife is supported, and A' the moving knife.

Attached to the block A are L-shaped brackets B B, which may be adjustable vertically. The horizontal portions of these brackets are slotted at b, and resting on such horizontal portions, with depending extensions entering said slots, are blocks B'. Said blocks are secured by screw-bolts b', passing up from below into the depending extensions, the heads of

such bolts spanning the slots. These blocks support the screw-pivots C, upon which the saddle C' and the parts borne thereby oscillate.

It will be noticed that by the use of the L- 55 brackets and the adjustable bearing-blocks I am enabled to adjust either or both ends of the saddle horizontally without loosening the pivot-screws or otherwise destroying its vertical position. This could not be done with the construction shown in the previous machine.

The saddle C' in my improved machine passes below the oscillating rod H, instead of above it, while the foot D and the barrel-supporting standard D', which in my said patent 65 were in one piece, I now make in two pieces, for reasons now to appear. The foot D swings upon the pivotal screws d, passing into the same from the saddle C', and the standard is adjustably bolted to the rounded vertical faces 70 d' of the foot by bolts passing through elongated openings in the standard, as shown, the lower extremity of the standard being also correspondingly rounded, as shown. This rounded line, along which the standard is moved in 75 adjustment, is the circumferential line of a circle having its center at or near the point at which the nails are severed from the plate. This center is indicated at x, and enables me to adjust the standard and barrel laterally in 80 either direction without moving the nose of the barrel from its position. The ball H' upon the end of the oscillating rod H is centered in a socket in the flaring head of a pin, H², passing through the segment E and supported 85 in the standard D'. The teeth upon the segment E mesh with the teeth upon the barrel D², and give it the customary half-revolution, the segment being actuated to this duty by the arm E', secured in the head of the rod H, the 90 upper point of the arm entering between the projection f and the adjustable angle-piece f', bolted to the segment. By thus communicating power to the segment near its center, instead of at the point, at which it was done in 95 my former machine, friction is lessened to a very considerable extent. The brackets B B are each provided with downward extensions b² b³, through which passes the bolt B², which draws the brackets together. 100

The holding-springs K, by which the nail-plate is held, are secured to the nose of the

barrel by bolts *k*, and in order to permit the use of springs of the customary length with a short nose of gentle taper I recess the body of the barrel at the proper places, so the rear ends of the springs may extend thereinto, as shown in Fig. 2. I thus economize in the length of the nose, and avoid the interference with the knife-block, which would result if the nose were made so tapering as to permit the springs to extend outside of the barrel. The springs also act better than when set upon a wider angle.

I claim—

1. The barrel and its standard *D'*, the latter being adjustable along a circling line, as specified, and both barrel and standard swinging to and from the knives, in combination with the saddle upon which the standard is supported, substantially as described.
2. In a nail-plate feeder, the combination of the barrel, the standard *D'*, and foot *D*, the standard being adjustably secured upon the foot, substantially as specified.
3. In a nail-plate feeder, the combination of the pivoted saddle, the foot pivoted in the saddle, the standard *D'*, adjustable upon the

foot, and the barrel and its operating segment supported upon the standard, all combined and operating substantially as specified.

4. The combination, in a nail-plate feeder, of the foot *D*, the standard *D'*, with the flaring head, pivotal pin *H*, the ball *H'*, and the segment *E*, substantially as specified.

5. The combination, in a nail-plate feeder, of the saddle and the parts borne thereby, with the *L*-brackets, and the adjustable pivot-blocks supported on such brackets, substantially as specified.

6. The combination, in a nail-plate feeder, of the vibrating segment for operating the barrel and its actuating-arm, the latter being connected to the segment at the point and in the manner shown.

7. In a nail-plate feeder, the barrel and its nose, in combination with the springs, the barrel being recessed to receive the rear ends of the springs, substantially as specified.

JOHN C. GOULD.
